HYDRAULIC CONTROL MECHANISM

Anthony L. Lado, Rome, N. Y., assignor, by mesne assignments, to Rome Grader Corporation, Rome, N. Y., a corporation of New York

Application August 19, 1946, Serial No. 691,579

2 Claims. (Cl. 121—41)

1

This invention relates to a control mechanism, particularly a mechanism used to control an object which is moved by fluid under pressure.

An object of the invention is to provide an improved control mechanism which will easily and accurately control a movable article.

Another object of the invention is to provide an improved control mechanism which may be set to move an article any desired distance and will permit the motion of the article to be accomplished subsequently, the article being accurately stopped when its motion has brought it to a desired point.

Another object of the invention is to provide an improved control mechanism which may be used to move an article selectively in either of two or more directions.

Another object of the invention is to provide an improved control mechanism which may move an article directly from one position to any other desired position within its range of possible motion.

Another object of the invention is to provide an improved control mechanism which may reverse the motion of an article at any point in its travel.

Another object of the invention is to provide an improved control mechanism which will be simple in construction.

Another object of the invention is to provide an improved control mechanism which will be easily assembled and disassembled.

Another object of the invention is to provide an improved control mechanism which will balance fluid pressures within the control.

Other objects will hereinafter appear.

The invention will be better understood from the description of one practical embodiment thereof, illustrated in the accompanying drawings, in which:

Figure 1 is a somewhat diagrammatic longitudinal sectional view of a control mechanism embodying my invention, this being designed primarily for use as a part of the steering gear of a vehicle;

Figure 2 is a fragmentary horizontal plan section, taken on the line II—II of Figure 1, and showing a neutral position of the exhaust ports;

Figure 3 is a fragmentary transverse sectional view taken on the line III—III of Figure 1; and

Figures 4 to 8 are longitudinal sectional views, similar to the right hand part of Figure 1 but showing various positions which may be assumed by the ports in the operation of the control.

The apparatus shown in the drawings is in-

2

tended for moving an article in either two opposed directions by varying amounts, as may be determined by the operator, as for instance the moving of the steering wheel or wheels of a land vehicle, or the rudder of air or water craft, or the like.

The part actuated need not be a control element, but can be any movable article which it may be desired to move into any one of a plurality of positions, but the types of control elements above mentioned furnish a convenient example, and so are chosen for the purposes of illustration and explanation, it being understood that the invention is not, however, limited to such elements.

To show a very simplified control, the operator has been provided, in the device illustrated, with a manually movable crank 1 fixed to an arm 2 which is fastened to a threaded shaft 3, as by the clamping bolt 4.

The shaft is shown as supported in a bearing 5, carried by a stationary bracket 6, the shaft being held from axial movement by a flange or collar 7 engaging one side of the bearing and the hub portion of the arm 2 engaging the other side thereof.

The threaded portion 8 of the shaft 3 engages the internal thread of nut 9, pivotally carried at the end of a lever 10, the center of which is shown as pivoted at 11 on an extending lug 12 of the control apparatus. The upper end of the lever 10 is pivoted to a link 13 which in turn is pivoted to a control valve sleeve 14.

Sleeve 14 is shown as cylindrical, having an open inner end and a closed outer one to which the link 13 is pivoted, and may reciprocate within a cylinder 15.

The cylinder 15 has formed in its inner surface four recesses, which for clarity of illustration have been shown above and below the sleeve and to one side thereof. The recess 16 below the sleeve is connected by the fittings and pipe 17 to a source of fluid under pressure, such as a pump P delivering oil, other liquid, air, gas or any other fluid pressure transmitting medium to the apparatus.

In the example illustrated, it is assumed that the fluid used will be of liquid nature rather than a gaseous one, and the parts are therefore smaller and heavier in their proportions because of the high pressures which may be practicably attained with such liquid or hydraulic media.

Above the sleeve are shown two spaced recesses 18 and 19 in axial alignment with each other, the former of which is connected by fittings and a pipe or tube 20 to the right hand end of a cylinder

21, and the latter of which is connected by fittings and a pipe or tube 22 to the left hand end of the same cylinder 21.

The recess 23 at the side of cylinder 15 is connected by fittings and a pipe or tube 24 to a point of discharge, such as a tank or sump T for receiving discharged fluid and refurbishing it to the pump P which supplies it under pressure to pipe 17.

Within the sleeve valve 14 is a valve piston 25 which is provided with two passages, shown as peripheral grooves 26 and 27, and this piston is connected fixedly to a piston rod 28 which extends through packing 29, held in a gland in the end of cylinder 15, into the cylinder 21.

Within this last mentioned cylinder the piston rod is provided with a piston 30 carrying packing 31 which may be caused to travel within a cylinder 21 by differential pressure of the fluid selectively supplied through pipes 20 and 22 to the opposite ends of the cylinder.

The piston rod 28 also continues through a cylinder head 32 at the end of cylinder 21 remote from the valve mechanism into a second cylinder 33 which is closed on its further end by a head 34.

The cylinder head formed by the end of valve cylinder 15, the head 32, and the head 34 are clamped together by through bolts and nuts 35.

Within cylinder 33 and fixed to the piston rod 28 is a piston 36, provided with packing 37, and from heads 32 and 34 communication with the interior of cylinder 33 is established by fittings and tubes or pipes 38 and 39, respectively, which connect with ports through the heads 41 and 40 extending to the interior of a cylinder 42.

In cylinder 42 is a piston 43 provided with suitable packing 44 and fixed to a piston rod 45 passing through the head 41, which carries a packing gland and suitable packing material 46.

The end of piston rod 45 is shown as provided with an eye or ring 47 by which it may be connected to the control element or other part which it is desired to move.

Returning to describe the control valve mechanism in more particularity, the sleeve 14 is provided with a number of ports therethrough as follows:

Through the bottom of the sleeve 14; that is, through the portion in alignment with recess 16, are ports 48 and 49, these being so spaced that the distance between them is at least equal to the distance between the extreme edges of grooves 26 and 27, thus both ports may be closed when piston 25 is in the neutral position shown in Figure 1.

Diametrically opposite port 48, and arranged to communicate with groove 26 and recess 18 is a port 50, and opposite port 49 and arranged to communicate with groove 27 and recess 19 is a similar port 51.

Between these ports, and also in alignment with recesses 18 and 19, are two ports 52 and 53, these being spaced so that the over-all distance across them is no greater than the length of that part of the piston between grooves 26 and 27, so that both ports may be closed by the central part of the piston when the ports are in a neutral position, as in Figure 1.

In longitudinal alignment with ports 52 and 53, but offset to the side of the sleeve to communicate with recess 23, are, respectively, two ports 54 and 55.

The operation of the device is as follows:

Starting with the parts in the position indicated in Figure 1, and assuming that it is de-

sired to move the article connected to ring 47 to the left, the operator rotates handle 1 to draw the nut 9 toward bracket 6, thus, through the lever 10 and link 13, moving the sleeve valve 14 to the left—say, to the position indicated in Figure 4.

It will be apparent that this motion of the sleeve brings ports 48 and 50 into alignment with groove 26 and brings ports 53 and 55 into alignment with groove 27, at the same time causing ports 52 and 54 to be covered by the central portion of the piston and ports 49 and 51 to be covered by the left hand end portion thereof. Thus fluid under pressure is permitted to flow from pipe 17 and recess 16 through port 48, groove 26, port 50, recess 18 and pipe 20 to the right hand end of cylinder 21 to move piston 30 to the left.

Simultaneously, the passage from the left hand end of cylinder 21 through pipe 22 permits the discharge of fluid through recess 19, ports 53, groove 27, port 55, and pipe 24 to the receiving tank or sump T, thus permitting the leftward movement of piston 30.

The motion of piston 30, of course, moves piston 36 in the same direction, and so forces fluid through pipe 39 and head 40 into the right hand end of cylinder 42, thus driving piston 43 and connection rod 45 to the left to move the article.

This motion of the pistons continues until the parts reach the positions indicated in Figure 5, in which the piston valve 25 has moved until its right hand end again covers ports 48 and 50, its central portion covers ports 52, 53, 54 and 55, and its left hand end still covers ports 49 and 51. In this position, no fluid can flow through the control and the parts are brought to rest.

In Figure 6, the sleeve has been moved in the opposite direction—to the right—to a position beyond that which it had occupied at its more or less central original position of Figure 1, and it is apparent that fluid may now flow from pipe 17 and recess 16, through port 49, groove 27, port 51, recess 19, and pipe 22 to the left hand end of cylinder 21, and that fluid may now be discharged from the right hand end of this cylinder through pipe 20, recess 18, port 52, groove 26, port 54, recess 23, and pipe 24 to the sump T. The fluid now will move piston 30, together with pistons 36 and 43, to the right until the piston valve 25 has reached the position shown in Figure 7, where once again all the ports are closed.

Figure 8 shows a setting of the sleeve valve to move the pistons still farther to the right—to their furthest distance in this direction. The communications established and directions of motion are the same as in Figure 6.

Even where the sleeve has been moved to the extreme position shown in Figure 8, where ports 52 and 53 are both in communication with recess 18, the parts function correctly because the central portion of the piston 25 covers port 54 so long as groove 26 is in communication with ports 52 and 54, so that there can be no by-passing of the fluid which would interfere with the operation.

To return the parts to their original position it is only necessary to return the sleeve valve to its initial position, as in Figure 1, when the fluid passes through the various passages as it did in Figure 4, until the piston 25 resumes its original neutral position.

From the above it is apparent that any motion of the sleeve valve will cause a corresponding

motion of the several pistons, the parts always coming to rest when piston valve 25 is in such a position that its ends cover ports 48, 49, 50 and 51 and its central portion covers ports 52, 53, 54 and 55 and that the amount of motion imparted to piston 43 therefore is directly proportional to the amount of motion imparted to the sleeve 14.

The actual distance travelled by piston 43, of course, may be varied by the proportioning of the diameters of the cylinders 33 and 42, while the force which as applied can be determined by the areas of the pistons in these two cylinders, as well as that in cylinder 21, and the pressure of the fluid supply.

Both the piston valve 25 and the sleeve 14 are so arranged that all pressures acting upon them are balanced, so that the sleeve may be moved by any motion which is sufficient to overcome the friction between the piston 25, the sleeve 14, and the cylinder 15. Also, the ports are opened and closed somewhat gradually so that the smoothness of operation is assured.

It will be observed that if the motions of the sleeve 14 and of the piston valve 25 are very short, ports 52 and 53 can be merged into a single port, and so likewise can ports 54 and 55, but this can only be done when the length of the combined port will be of less length than the distance between recesses 18 and 19, because otherwise fluid will be by-passed between these recesses interfering with the operation of the apparatus.

While I have described the illustrated embodiment of my invention in some particularity, obviously many other embodiments, modifications and variations will occur to those skilled in this art, and I do not, therefore, limit myself to the precise details shown and described herein, but claim as my invention all embodiments, modifications and variations coming within the scope of the appended claims.

I claim:

1. An hydraulic control device comprising a source of fluid under pressure, a cylinder, a load moving piston movable therein, a piston rod fixed to the piston and carrying a cylindrical valve part provided with two annular grooves, a sleeve slidably fitting the exterior of the valve part carried by the piston rod and having ports therethrough angularly disposed about the sleeve, a fixed cylindrical casing slidably receiving the exterior of the sleeve and having four recesses on its interior which may selectively be brought into alignment with the ports through the sleeve by the axial movement of said sleeve, one said recess being connected to the discharge

side of the source of fluid under pressure, another recess being connected to the intake side of the source of fluid under pressure, a third recess being connected to one end of said cylinder, the fourth recess being connected to the opposite end of said cylinder, and positive connections between the piston and its load, said two annular grooves being selectively registerable with certain of said sleeve ports and certain of said recesses to effect a movement of said piston rod in a selected axial direction.

2. An hydraulic control device comprising a source of fluid under pressure, a cylinder, a load moving piston movable therein, a piston rod connected into the piston and extending beyond the cylinder, a cylindrical valve part fixed to said piston rod and having two annular grooves, a tubular sleeve slidably fitting said valve part and provided with ports therethrough annularly spaced about the sleeve, a fixed valve cylinder slidably receiving the sleeve and having two axially aligned recesses connected with the opposite ends of the cylinder, the valve cylinder having two additional interior recesses out of axial alignment with each of the two first mentioned recesses and with each other, and connections between one of the last mentioned recesses and the outlet side of the source of fluid under pressure and between the other of the last mentioned recesses and the intake side of the said source of fluid under pressure, said two annular grooves being selectively registerable by relative movement of said sleeve and said cylindrical valve part on said piston rod, with certain of said recesses to effect an axial movement of said piston rod.
